HEAD FOR A TIKI TORCH

James D. Reese, 11937 Avenue 274,
Visalia, Calif. 93277

Filed Apr. 28, 1971, Ser. No. 138,399

Term of patent 14 years

Int. Cl. D26—02, 05

U.S. Cl. D48—24

FIG. 1 is a top plan view of a head for a tiki torch showing my new design;

FIG. 2 is a side elevational view thereof;

FIG. 3 is a bottom plan view thereof; and

FIG. 4 is a perspective view thereof.

I claim:

The ornamental design for a head for a tiki torch, as shown.
